Primary Examiner — T Chase Nelson*Assistant Examiner* — Rachel Wolfe(74) *Attorney, Agent, or Firm* — Culhane Meadows PLLC; Aasheesh Shravah(57) **CLAIM**

The ornamental design for a modular light, as shown and described.

DESCRIPTION

FIG. 1 is a perspective view of a modular light with a light portion in an unrotated configuration;

FIG. 2 is a perspective view of the modular light with the light portion in a rotated configuration;

FIG. 3 is a front view of the modular light with the light portion in the unrotated configuration;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in the figures illustrate portions of the modular light that form no part of the claimed design.

1 Claim, 6 Drawing Sheets(56)
